UNITED STATES PATENT OFFICE

KARL SCHMID, OF COLUMBIA, PENNSYLVANIA

RATCHET MECHANISM FOR OPERATING BENCH VISSES

Application filed December 17, 1928. Serial No. 326,633.

This invention is a mechanical power apparatus especially designed for operating a bench vise or the like and includes means for converting intermittent reciprocatory motion into intermittent rotary motion.

More particularly the invention comprises a ratchet mechanism associated with a rotary shaft and arranged to be operated by a foot or hand lever for the purpose of imparting a step-by-step rotary movement to the shaft.

In a preferred embodiment of the invention, I provide a gear wheel keyed to the shaft and arranged for engagement with some other mechanical element of an apparatus to be operated such as, for instance, the movable jaw of a bench vise.

The invention has for one of its objects the provision of a mechanical power apparatus of the type indicated by which a succession of relatively short strokes of either a hand or foot lever may be caused to advance a power shaft step by step, and wherein means are included for locking the shaft against retrograde movement during the interval between successive power strokes.

A further object of the invention is to provide a mechanical power device including a rotary pawl and ratchet mechanism wherein means for retracting the pawl after each power stroke is mounted on and concentric with the driven power shaft.

Another object of the invention is to provide a pawl and ratchet mechanism including a driving pawl and a locking pawl with a release lever arranged to operatively engage both of said pawls for simultaneously releasing the same when it is desired to allow the power shaft to rotate freely in either direction.

A still further object of the invention is to provide a power mechanism of the type indicated that is simple but compact in construction and which is particularly adapted for operating the movable jaw of a bench vise or the like.

These and other objects will become apparent from the following specification read in connection with the accompanying drawings wherein I have shown the inven-

tion operatively associated with a bench vise.

In the drawings,

Fig. 1 is a side elevation of the invention as used with a bench vise, parts of the latter being broke away;

Fig. 2 is a front elevation of the same;

Fig. 3 is a sectional view taken on line 3-3 of Fig. 2 with the movable jaw of the vise omitted, and

Fig. 4 is a fragmentary detailed view of the pawl releasing lever.

Referring more particularly to the accompanying drawings wherein like reference numerals designate like parts throughout the numeral 1 indicates generally the top of a work bench or similar support. To the under-side of the top 1, a pair of brackets 2-2a are secured, said brackets extending forwardly and upwardly as shown more clearly in Fig. 1. The brackets are arranged in spaced relation as shown in Figs. 2 and 3 and each bracket terminates in a bearing member 3-3a respectively, said bearings being horizontally aligned to receive and support for rotation therein, a shaft 4. As shown in Figs. 2 and 3, the shaft 4 extends beyond both bearing members 3-3a, terminating at one end in an annular flange 5. The opposite end 6 of the shaft is threaded and provided with a nut 7 for the purpose of preventing accidental displacement of the shaft with respect to the bearings. A sleeve 8 is mounted upon the shaft 4 between the bearing 3a and the flange 5 and the coil spring 9 mounted concentrically upon the shaft beyond the sleeve functions to urge the sleeve into engagement with the bearing 3a. Attention is here directed to the opposed inclined cam faces 10 and the abutting shoulders 11 carried by the adjacent faces of the sleeve 8 and the bearing member 3a. The operation and function of these elements will be hereinafter fully described.

The sleeve 8 carries a radially extending arm 12, lying to the rear of the shaft 4 and between the shaft 4 and the front edge of the bench top 1. The arm 12 terminates in an eye member 13 in which a stub shaft 14 is fixedly secured by a set screw or the like 15. As shown in Fig. 3 the stub shaft 14 lies parallel to the

main shaft 4 and between the main shaft and the front edge of the support 1, while from Figs. 1 and 2 it will be seen that the stub shaft also lies somewhat above the main shaft 4. The stub shaft 14 extends beyond the bearing member 3a and terminates opposite to the periphery of a ratchet wheel 16 fixedly secured to the main shaft 4, said ratchet wheel being provided with ratchet teeth 17 on its periphery.

10 A driving pawl 18 for the ratchet wheel 16 is pivotally mounted on the end of the stub shaft 14 and depends therefrom into operative engagement with the ratchet teeth 17.

15 A pin 19 may be provided in the end of the stub shaft 14 to prevent displacement of the pawl 18.

An operating link or treadle hanger 20 for the pawl 18 is pivotally mounted upon the shaft 14 at a point substantially central thereof; said link 20 for this purpose carries an eye member 21 through which the shaft 14 passes. In order to maintain eye member 21 in a centralized position on the stub shaft 14, coil springs 22 and 23 may be disposed on said shaft between said eye and the opposite ends of the shaft. The coil spring 23 is preferably tensioned to apply a bias to the pawl 18 for the purpose of maintaining the pawl in engagement with the ratchet wheel; said spring for this purpose having its opposite ends engaged with the eye member 21 and the pawl 18.

The bearing 3a is provided with an auxiliary bracket arm 24 which carries a second stub shaft 25 extending parallel to the main shaft 4 and overlying the ratchet wheel 16. The stub shaft 25 supports a pivoted locking pawl 26 which is biased by gravity into operative engagement with the ratchet wheel 16, said pawl functioning to prevent retrograde movement of the ratchet wheel between successive power strokes of the pawl 18. The stub shaft 25 may conveniently be provided with a slight shoulder 27 to operatively position the pawl 26 with respect to the wheel 16 and a pin 28 is provided to prevent displacement of the pawl.

Means are provided for releasing both the driving pawl 18 and the locking pawl 26 when desired in order to permit free rotation of the shaft in either direction. This means comprises a pawl release lever 29 shown more clearly in Fig. 4. The lever 29 is pivotally mounted on stub shaft 25 between the pin 28 and the pawl 26. As shown in Figs. 2 and 3 the lever 29 is positioned to lie immediately adjacent to the outside face of the ratchet wheel 16 and is biased by gravity to a position in which the arm 30 thereof rests upon the hub or collar 31 of the ratchet wheel 16. As hereinbefore stated, the pawls 18 and 26 both engage the toothed periphery of the wheel 16 and in order to establish an operative relation between said pawls and the

lever arm 30, said pawls are provided with lateral extensions or wings 32 and 33 overlying lever arm 30 and arranged to be engaged thereby when the lever 29 is operated. It will of course be understood that the arm 30 engages the wings 32 and 33 from beneath and functions to raise the pawls clear of the ratchet teeth 17.

The pawl operating link 20 is arranged to be operated by the foot of an operator and to this end it is extended to a position near the floor and is provided at its lower extremity with a foot pedal 34. The link 20 is offset as at 35 in order to clear the bracket arm 2a and to obviate straining the associated parts of the apparatus due to abnormal side strains incident to the operation of the link 20 a strap or yoke 36 is provided opposite said offset portion 35 and embracing bracket 2a. The strap 36 has its opposite ends secured to the link 20 above and below the offset portion 35 thereof. This construction is clearly shown in Fig. 2.

The operation of the apparatus as thus far described will now be readily understood. Upon depression of the foot pedal 34 the link 20 moves downwardly oscillating the arm 12 in a counter-clockwise direction as viewed in Fig. 1. This movement serves to simultaneously rotate the ratchet wheel 16, through a driving impulse from the pawl 18, and to rotate the sleeve 8 also in a counter-clockwise direction, the arm 12, the sleeve 8 and the pawl 18 moving together as a unit. Due to the inclined cam faces 10 carried by the sleeve 8 and the bearing 3a, the sleeve and the parts carried thereby are caused to move longitudinally of the shaft 4 towards the left as viewed in Fig. 2. This movement of the sleeve compresses the coil spring 9, which resists movement of the sleeve toward the flange 5. When pressure is relieved from the pedal 34, the spring 9 urges the sleeve 8 to the right as shown in Fig. 2 and under the action of the inclined cam faces 10, said sleeve is caused to rotate in a clockwise direction as viewed in Fig. 1, until the shoulders 11 abut at which time the foot pedal 34 is in its elevated position and the driving pawl 18 is in position for another power stroke. During the reverse movement of the pawl 18, the pawl 26 prevents retrograde movement of the wheel 16 and the shaft 4. As hereinbefore suggested the pawl release lever 29 may be operated at any time to provide for free rotation of the shaft 4 in either direction.

In order to adapt the apparatus as described for use in connection with a bench vise, I provide a gear-wheel 37 keyed to the shaft 4. Immediately above the gear 4 and in overhanging relation with respect to the bench top 1, I mount a bench vise 38 comprising a fixed jaw 39 and a movable jaw 40. The latter is provided on its under surface with a rack 41 which is in mesh with the

gear 37. By manipulation of the foot pedal 34 as above described the movable jaw 40 of the vise may quickly move into powerful clamping engagement with the fixed jaw 39 or with a piece of work inserted therebetween. Attention is directed to the fact that by this arrangement, as shown more clearly in Fig. 2, the pawl releasing lever 29 is disposed laterally of the path of movement of the jaw 40 whereby to provide for ready manipulation of said lever in all positions of the vise jaws.

From the foregoing description it is apparent that I have devised a simple, powerful and compact ratchet mechanism, including a rotary power shaft which may be readily connected to simple mechanical devices, such as a bench vise or the like; that by disposing the pawl and lever restoring mechanism concentrically with respect to the power shaft, the mechanism is made exceedingly rigid and compact; that by providing a release lever for the operating pawls the power shaft may be rotated freely in either direction when desired and that by arranging a single lever to operate both the driving pawl and the locking pawl of the ratchet mechanism, the mechanism is simplified and the number of operating elements is reduced. In conclusion, it is to be noted that while I have here shown and described a preferred embodiment of my invention, such illustration and description are for the purpose of example only and not for defining the limits of my invention, which are to be determined from the scope of the appended claims.

What I claim as new is:

1. A ratchet mechanism including a shaft mounted for rotation, a peripherally toothed ratchet wheel secured to the shaft, a pawl mounted for rotary oscillation and operatively engaging the teeth of the ratchet wheel, means for oscillating the pawl to intermittently drive the ratchet wheel, cam means associated with the pawl oscillating means for moving the pawl laterally of the ratchet wheel during the power stroke, and spring means energized by said lateral movement of the pawl for restoring the pawl after the expiration of the power stroke.

2. A ratchet mechanism including a shaft, a ratchet wheel secured thereto, a driving pawl associated with the ratchet wheel, means for driving the pawl and means for restoring the pawl to normal position after each power stroke, said last mentioned means including an oscillatory sleeve mounted on the shaft and spring means tending to resist movement of the sleeve.

3. The apparatus described in claim 2 wherein means are associated with the sleeve for imparting thereto a longitudinal movement when said sleeve is rotarily oscillated on the shaft.

4. A ratchet mechanism including a pe-

ripherally toothed ratchet wheel mounted for rotation, a pawl operatively associated with the toothed periphery of the wheel and movable rotarily and laterally thereof, means for moving the pawl rotarily to drive the wheel, cam means associated with the pawl for shifting the pawl laterally in one direction during the power stroke of the pawl, and spring means energized by said lateral movement of the pawl, and functioning to laterally shift the pawl in the opposite direction following the expiration of the power stroke, said cam means being provided with an inclined face which functions to rotate the pawl in the opposite direction to that traveled by it during the power stroke.

5. In a ratchet mechanism including a ratchet wheel, a driving pawl therefor and means for operating said pawl, pawl restoring mechanism including a sleeve mounted for rotary oscillation about the axis of said ratchet wheel and operatively connected to the driving pawl, a stop member engaged by the sleeve, said sleeve and stop member having cooperating inclined cam faces, and a spring member urging the sleeve against said stop member.

6. The apparatus described in claim 5 wherein the cam faces of the sleeve and stop member define cooperating shoulders which limit the rotary movement of the sleeve in one direction and define the normal position of the sleeve and pawl.

7. In a ratchet mechanism, a ratchet wheel, a sleeve mounted for rotary oscillation about the wheel axis, a stub shaft carried by the sleeve, a pawl mounted on said shaft and operatively engaging the ratchet wheel, and a pawl operating member mounted on the shaft for rotarily oscillating the sleeve to actuate the pawl.

8. The apparatus described in claim 7 wherein coil springs are mounted on the stub shaft on either side of the pawl operating member whereby to centralize said member on the stub shaft.

9. The apparatus described in claim 7 wherein a coil spring is mounted on said stub shaft on each side of the pawl operating member whereby to centralize said means with respect to the shaft, one of said springs being tensioned between said pawl operating member and said pawl whereby to urge the pawl into engagement with the ratchet wheel.

10. A ratchet mechanism including a shaft, a ratchet wheel secured thereto, a reciprocatory sleeve mounted on the shaft, driving means carried by the sleeve and engaging the ratchet wheel, means for actuating the driving means to advance the ratchet wheel step by step, cooperating means carried by the sleeve and a part fixed with respect thereto for shifting said sleeve laterally when the driving means is actuated, and resilient

means opposing the shifting movement of the sleeve.

11. A ratchet mechanism including a shaft, a ratchet wheel secured thereto, a reciprocatory sleeve mounted on the shaft, driving means carried by the sleeve and engaging the ratchet wheel, means for actuating the driving means to advance the ratchet wheel step by step, cooperating means carried by the sleeve and a part fixed with respect thereto for shifting said sleeve laterally when the driving means is actuated, and resilient means opposing the shifting movement of the sleeve, said resilient means comprising a spring carried by the shaft and engaging the sleeve.

12. A ratchet mechanism including a shaft, a peripherally toothed ratchet wheel secured thereto, means engaging the toothed periphery of the ratchet wheel for intermittently driving the same, means for actuating the driving means, said driving means under the action of the actuating means moving rotarily and laterally, and resilient means opposing the lateral movement of the driving means and functioning to restore said driving means to normal position.

13. A ratchet mechanism including a shaft, a ratchet wheel secured thereto, a pawl mounted for lateral and rotary movement and operatively associated with the ratchet wheel for intermittently driving the ratchet wheel, a link for actuating the driving pawl, said driving pawl under the action of the actuating link moving rotarily and laterally, and a spring mounted adjacent the driving pawl and opposing the lateral movement thereof, said spring functioning to restore the driving pawl to its normal position following each power stroke thereof.

14. In a ratchet mechanism, a ratchet wheel, a sleeve mounted for rotary oscillation about the axis of the wheel, a stub shaft carried by the sleeve, a pawl mounted on the shaft and engaging the ratchet wheel, a link carried by the shaft for operating the pawl and a coil spring surrounding the shaft and torsionally tensioned between the link and pawl whereby to position the link on the shaft, and to resiliently urge the pawl into engagement with the ratchet.

15. A ratchet mechanism including a shaft, a ratchet wheel secured thereto, a driving pawl associated with the ratchet wheel, means for driving the pawl, means for restoring the pawl to normal position after each power stroke, said last-mentioned means including an oscillatory sleeve mounted on the shaft, means associated with the sleeve for imparting thereto a longitudinal movement when the sleeve is rotarily oscillated on the shaft, and spring means tending to resist the longitudinal movement of the sleeve and biasing said sleeve to a normal position at one limit of its range of movement.

16. In a ratchet mechanism, a ratchet wheel, an intermittently actuated pawl for driving the ratchet wheel, means for operating the pawl, means for shifting the pawl laterally in one direction during its power stroke, spring means opposing the lateral shifting of the pawl, said spring means arranged to automatically shift the pawl laterally in the opposite direction at the expiration of the power stroke, and stop means associated with the pawl, shifting means for arresting the pawl in a position for another power stroke.

17. In a ratchet mechanism including a shaft, a ratchet wheel mounted thereon, a pawl for driving the ratchet wheel step by step and means for intermittently actuating said pawl, the combination with the pawl actuating means, of means for causing a lateral shifting of the pawl during its power stroke, and resilient means associated with said last mentioned means for automatically shifting the pawl laterally in the opposite direction to restore the pawl to normal position at the expiration of the power stroke.

18. In a ratchet mechanism, a shaft, a ratchet wheel secured to the shaft, a pawl for intermittently driving the ratchet, and means for actuating the pawl, the combination with said pawl actuating means, of cam means for shifting the pawl laterally during its power stroke, and spring means placed under compression by the lateral shifting of the pawl actuating means and automatically released at the expiration of the power stroke, whereby the pawl is restored to normal position following each power stroke.

19. In a ratchet mechanism, a shaft mounted for rotation, a peripherally toothed ratchet wheel secured to the shaft, a sleeve mounted on the shaft for rotary oscillation, a stub shaft carried by the sleeve in spaced parallel relation to the first mentioned shaft, a driving pawl pivotally mounted on the stub shaft and operatively engaging the toothed periphery of the ratchet wheel, means to rotarily oscillate the sleeve, a second stub shaft fixedly mounted in spaced parallel relation with the other two mentioned shafts, a locking pawl pivotally mounted on said second mentioned stub shaft and engaging the toothed periphery of the ratchet wheel to lock the same against retrograde movement, and a pawl releasing lever mounted on the second mentioned stub shaft and movable about the axis thereof in a plane perpendicular to the axes of the three shafts and adjacent to the ratchet wheel, said pawls being each provided with a lateral extension overhanging the releasing lever whereby the pawl releasing lever may be operated to simultaneously release the driving pawl and the locking pawl.

20. In a ratchet mechanism, a shaft mounted for rotation, a peripherally toothed ratchet wheel secured thereto, a sleeve mounted for

rotary oscillation and rectilinear reciproca-
tion about the shaft, a stub shaft carried by
the sleeve and disposed substantially parallel
to the first mentioned shaft, a driving pawl
pivotally mounted on the stub shaft above
5 the toothed periphery of the ratchet wheel
and operatively engaging the same, means for
rotating the sleeve and pawl to impart a
power impulse to the ratchet wheel, cam
means associated with the sleeve to shift the
10 same laterally during rotation thereof, and
spring means energized by the shifting of the
sleeve, said last mentioned means functioning
to retract the sleeve and pawl at the end
of the power stroke.

21. In a ratchet mechanism, a shaft mounted
for rotation, a peripherally toothed
ratchet wheel secured thereto, a sleeve
20 mounted for rotary oscillation and rectilinear
reciprocation about the shaft, a stub shaft
carried by the sleeve and disposed substan-
tially parallel to the first mentioned shaft, a
driving pawl pivotally mounted on the stub
25 shaft above the toothed periphery of the
ratchet wheel and operatively engaging the
same, means for rotating the sleeve and pawl
to impart a power impulse to the ratchet
wheel, cam means associated with the sleeve
30 to shift the same laterally during rotation
thereof, spring means energized by the shift-
ing of the sleeve, said last mentioned means
functioning to retract the sleeve and pawl
at the end of the power stroke, and a stop for
35 limiting the retraction of the pawl and sleeve
to properly position the pawl for another
power stroke.

In testimony whereof I hereunto affix my
signature.

KARL SCHMID.
